UNITED STATES PATENT OFFICE

HUGO SCHRÖDER, OF ESSEN-ON-THE-RUHR, GERMANY

COKE OVEN

Application filed November 28, 1925, Serial No. 71,877, and in Germany April 12, 1924.

My invention relates to improvements in coke ovens, and more particularly in coke ovens of the type in which the coking and heating chambers are disposed above the regenerators. The object of the improvements is to provide a coke oven of this type in which the wear of the brick-work of the coking and heating chambers and the regenerators is reduced, and with this object in view my invention consists in erecting the coking and heating chambers on vaults disposed longitudinally of the coking chambers and having a span such that each vault is disposed below a plurality of heating and coking chambers, and disposing the regenerator within the said vaults, the regenerator disposed in each vault cooperating with the heating and coking chambers disposed above the same. In the preferred construction each vault comprises two arches disposed one above the other, the lower arch being capable of a certain expansion. In my improved oven the regenerators are separated from one another by strong walls forming a part of the vaults, and they are separate from one another in the operation of the oven. The coking and heating chambers are supported on a rigid base provided by the vaults, so that the walls thereof, which are necessarily thin, are in a less degree subject to destruction by cracks. Further, the brick-work of the regenerators is not subject to destruction by the brick-work of the coking and heating chambers bearing thereon, the said brick-work being supported exclusively on the vaults.

For the purpose of explaining the invention two examples embodying the same have been shown in the accompanying drawings, in which the same reference characters have been used in all the views to indicate corresponding parts. In said drawings,

Fig. 1, is a sectional elevation taken on the line 1—1 of Fig. 2,

Fig. 2, is a sectional elevation taken on the line 2—2 of Fig. 1,

Fig. 3, is a sectional elevation taken on the line 3—3 of Fig. 4 and showing a modification, and

Fig. 4, is a sectional elevation taken on the line 4—4 of Fig. 3.

In the example shown in Figs. 1 and 2 the coke oven comprises a base indicated as a whole by the letter A and the coking chambers c and heating passages or flues m, d, g, k, h, i, n indicated as a whole by the letter B. The base A consists of a rigid horizontal top plate C and vaults comprising rigid walls a and arches b, b' supporting the said plate C. Each vault comprises two arches b and b', the lower arch b' being capable of a certain expansion independently of the upper arch b. The vaults a, b, b' are disposed longitudinally of the coking chambers c, and their span is such that three coking chambers and heating passages are disposed above each vault. By thus constructing the base A, the walls of the coking chambers have a rigid support thereon so that they are not injured by the yielding of the said base. Within each vault there is a regenerator e, f, and each regenerator cooperates with the set of heating passages disposed above the same. In the example shown in the figures the heating passages or flues d and g are connected to the regenerators e, and the heating passages or flues h and i are connected to the regenerators f. The heating passages m and n are connected respectively to the regenerators e and f and the regenerators adjacent thereto. Therefore each regenerator cooperates with three heating passages. The regenerators are separated by a transverse wall o into sections e¹ and e² (Fig. 2). At their ends the regenerators are connected with air and waste heat passages p, r and passages s and t connected with fresh air and waste heat channels u and v. The passages u and v are alternately used for passing air for supporting combustion through the previously heated regenerator sections e¹ and e² to the passages p and r and the flues, and for conducting the heated gases coming from the flues and passing through the passages p and r and the regenerators to the stack. Each regenerator may be directly provided with fresh air valves w and gates x. For distributing the gases within the checker-work of the regenerators horizontal partitions y are provided, which extend from the outer ends of the regenerator sections e¹ and e² to

points away from the inner ends thereof. The bottom parts of the regenerator sections located at the same sides of the oven are connected with one another through passages 7 5 insuring transmission of the heat from one regenerator to the other one.

In the modification shown in Figs. 3 and 4 the heating passages or flues d^1 are connected with the regenerators e^3 , f^3 through collecting passages z , and the regenerators are not subdivided by transverse walls, such as o . Above the regenerators there are horizontal collecting passages r^1 and p^1 which are connected with the flues so that the heating gases 10 flow through the flues successively in upward and downward direction. The gas is distributed within the regenerator by regulating the air pressure or draught.

By combining adjacent heating passages 20 or flues in groups and comparatively large regenerators I am enabled to construct a rigid base providing a strong support for the thin heating walls, and to separate the regenerators by strong walls, so that the regenerators are separate from each other also in 25 continuous operation of the oven.

My improved structure may also be used in compound coke ovens, that is ovens adapted to be heated by means of a preheated low 30 grade gas. In this case in the regenerator sections of one side the regenerators for heating gas and for air are alternately arranged, while at the opposite side the waste gases are 35 passed to the stack through all the regenerator sections.

In many cases the regenerator systems of old plants can be reconstructed according to the principles of my invention.

I claim:

40 1. A coke oven having a series of alternately-disposed coking chambers and heating chambers therefor arranged side by side, said chambers being elongated horizontally, a regenerator disposed beneath the series of 45 coking and heating chambers and of a width to be coextensive with the length of the series of chambers, said regenerator communicating with the aforesaid heating chambers, the regenerator also extending substantially parallel to the coking and heating chambers.

2. A coke oven having a series of alternately-disposed coking chambers and heating chambers therefor arranged side by side, said coking and heating chambers being elongated horizontally, regenerator chambers disposed beneath the series of coking and heating chambers and of a combined width to be substantially coextensive with the length of the series, the regenerator chambers 55 communicating with the said heating chambers each of said regenerator chambers extending substantially parallel to the coking and heating chambers, each of said regenerator chambers having a plurality of superposed arches, the upper of which supports 60 65

said coking and heating chambers which are disposed above the upper arch, each lower arch being capable of expansion independent of the structure resting thereupon, the length of the arches being parallel with the 70 length of said coking and heating chambers.

In testimony whereof I hereunto affix my signature.

HUGO SCHRÖDER.
